APPLICATOR FOR TUBULAR BANDAGE

Charles A. Hanington, Freeport, N. Y., assignor to The Scholl Mfg. Co., Inc., Chicago, Ill., a corporation of New York

Application April 24, 1956, Serial No. 580,405

5 Claims. (Cl. 128—157)

This invention relates to improvements in an applicator for a tubular bandage, the invention being highly desirable for the application of tubular bandages to various parts of the human body for the purpose of covering various types of wounds, afflictions, other injuries and ailments, or to serve as slings, traction sustaining means, and for many other reasons wherefore a physician or surgeon may deem a bandage necessary, the invention having many uses and purposes as will be apparent to one skilled in the art.

The instant invention, while used in the same general manner, is an improvement upon the applicator illustrated in the E. G. Hendrickson et al. Patent No. 2,456,507, issued December 14, 1948. Other applicators have also been developed for the proper placing of tubular bandages to various parts of the body, such as fingers, toes, arms, legs, and even the head; and the instant invention may be made in various sizes so as to function for the application of bandages to substantially any part of the body that may be temporarily inserted within an applicator during the fixing of the bandage. The applicator is in general of a type which telescopes over the portion of the body to which the bandage is to be attached and during the application of the bandage, the applicator will move a plurality of times in a telescopic relationship over the particular part of the body.

In certain instances applicators heretofore developed have proven objectionable, particularly in regard with the application of small bandages such as over the fingers or toes, owing to the fact that the applicator itself would contact the wounded portion of the body adding to the pain and aggravation of the patient, and possibly aggravation of the particular injury or affliction. With applicators of the type heretofore known, actual contact of the applicator and the injured part of the body was extremely difficult to avoid.

With the foregoing in mind, it is an important object of the instant invention to provide an applicator so constructed as to be adjustable in size in regard to that portion of the applicator that passes over a part of the body.

Another object of the invention is the provision of an applicator for a tubular bandage, comprising a plurality of spaced resilient fingers normally tending to further spread, with adjustable means movable to reduce the spreading of the fingers or to maintain the fingers in substantially parallel relationship, depending upon what is desired at the time of the particular application.

Another object of the invention is the provision of an applicator of the character set forth herein having a plurality of resilient fingers inherently tending to spread, with simple slidable means for adjusting the spread of the fingers at any time desired, and even during the application of a bandage.

It is also a feature of this invention to provide an applicator for a tubular bandage comprising a plurality of resilient wire skeleton fingers in general defining a tubular socket over which a tubular bandage may be

drawn and into which a part of the body is temporarily received during the application of the bandage, the fingers being joined together only at one end of the applicator.

A further feature of the invention resides in the provision of an applicator for a tubular bandage, which is simple in construction, and highly economical to manufacture in that it comprises merely a wire or wires bent to a desired shape, and a simple form of ring adjusting member, if the same is desired.

10 While some of the more salient features, characteristics and advantages of the instant invention have been above pointed out, others will become apparent from the following disclosures, taken in conjunction with the accompanying drawing, in which:

15 Figure 1 is a side elevational view of an applicator embodying principles of the instant invention;

Figure 2 is a longitudinal vertical sectional view through the structure of Fig. 1, with parts shown in elevation, and illustrating the operation of the applicator;

20 Figure 3 is a transverse vertical sectional view taken substantially as indicated by the line III—III of Fig. 1, looking in the direction of the arrows;

Figure 4 is a transverse sectional view through the applicator taken substantially as indicated by the line

25 IV—IV of Fig. 2;

Figure 5 is a side view of a section of tubular bandage of the type with which the applicator may be used;

Figure 6 is a transverse vertical sectional view through the bandage taken substantially as indicated by the line

30 VI—VI of Fig. 5; and

Figure 7 is a fragmentary elevational view illustrating the use of the applicator.

As shown on the drawings:

For purposes of convenience, the illustrated embodiment of the instant invention is illustrated in a size and shape highly desirable for use in applying a finger bandage, and the invention will so be described herein. However, it must be distinctly remembered that the device may be made in various sizes so that bandages may be applied over arms, legs, feet, the head, and other parts of the body besides fingers.

The instant invention may be constructed of a single wire, a pair of wires, or a greater number of wires, bent to a desired shape. If there is more than one wire utilized, 45 the wires are joined to each other at one end of the applicator. In the illustrated instance, the applicator is shown as having a total of four spaced resilient skeleton type fingers generally indicated by numerals 1, 2, 3 and 4. Each finger comprises an elongated loop of wire 5 having a rounded and closed outer end as indicated at 6. The two side sections of wire forming the loop are brought together into a shank portion 7 with both reaches of wire in juxtaposition, preferably side by side and substantially together. This bending of the wire provides a shoulder 50 formation as indicated at 8 in each of the wire lengths.

At the rear end of the shank section 7, both wires are given a shaping to cause an inherent tendency of the fingers to further spread. In the illustrated showing, this shaping is in the form of an outward arc as indicated at 9, 55 providing a shoulder as at 10 wherein the arcuate portion joins the shank part 7. The juxtaposed wire links are maintained in closely adjacent relationship and merge into a transverse portion 11 which is connected centrally to the corresponding portion of another finger as indicated at 12.

It will be noted that a single wire may be bent as above defined in order to make up the entire number of fingers and cross connections. More practically, however, one wire is utilized to form in an integral formation a pair of opposed fingers, such as the fingers 1 and 3, while another wire would be utilized to form the fingers 2 and

4. Then, the two pairs of opposed fingers would be turned at right angles to each other, and the cross connections 11 of each pair soldered, welded, brazed, or otherwise secured together as at 12. Thus, an integral unit is formed consisting of a plurality of elongated resilient fingers circumferentially spaced, and inherently tending to further spread away from each other to the extent allowed by the formations 9.

In order to effect a desired adjustment at any time as to the amount of spread of the fingers 1, 2, 3 and 4, a simple arrangement has been provided. This merely consists of applying a ring 13 over the shank portion 7 of the respective fingers. As seen clearly in Figs. 1 and 2, the ring embraces these shank portions 7 and is slideable between the shoulders 10 and the shoulders 8 defined on each finger. Looking at Fig. 2, the full line showing with the ring forward or toward the open end of the applicator against the shoulders 8, it will be seen that the fingers are maintained in substantially parallel relationship or at the minimum spread adjustment. When the ring is moved to the shoulders 10 as indicated by dotted lines in this figure, the fingers are permitted to spread apart to the maximum distance. Obviously, any intermediate position of the ring results in an intermediate spread adjustment.

The instant invention is preferably used with a tubular bandage of the character shown in Figs. 5 and 6 and indicated by numeral 14. This bandage may preferably be of a knitted gauze or equivalent material, and is inherently stretchable and elastic to a material degree, at least laterally. In the most simple form of application, a length of bandage is selected which is substantially twice as long as the portion of the finger to be covered. This entire length of bandage is drawn over the fingers of the applicator as seen in Fig. 7, and the forward position of the ring 13 facilitates the ease for placing the bandage on the applicator since it holds the fingers at their minimum spread position. The applicator with the bandage thereon is then telescoped over the finger 15, the edge of the bandage held against the finger, and the applicator withdrawn retaining the remainder of the bandage upon it. Then the applicator may be twisted as indicated at 16 and the applicator again telescoped over the finger, retroverting the portion of the bandage on the applicator over that already on the finger. On the inward movement of the applicator the remainder of the bandage will be applied to the finger, and the applicator, clean of bandage, may be readily withdrawn from the applied bandage. During this operation, the ring 13 may be moved as desired in order to effect the spread of the fingers and the stretching of the bandage.

Of course, in some instances, it is desirable to provide a bandage in three or four layers upon the finger, and in that event a longer length of bandage is utilized, and the applicator operated over the finger a sufficient number of times to utilize all of the bandage, or a sufficient number of times to effect the desired type of bandage.

With the instant invention, since the fingers are of the skeleton type, and the spread of the fingers may be adjusted at will, there is little or no likelihood of the applicator contacting the injured part of the body, if reasonable care is exercised in its use. By way of example, if the injury is lengthwise of the finger, the applicator may be rotated relatively to the finger so that the injury will be disposed in the space between adjacent fingers. Other ways of manipulating the applicator will be apparent to one skilled in the art.

From the foregoing, it is apparent that I have provided a simple form of applicator for a tubular bandage, which applicator is light in weight and economical to manufacture. The applicator may be used with ease and facility, both in applying the bandage to the applicator and then in applying the bandage to the body with the aid of the applicator, and tension upon the bandage and the de-

gree of spread of the fingers may be altered at will even during the application of the bandage.

It will be understood that modifications and variations may be effected without departing from the scope of the 5 novel concepts of the present invention.

I claim as my invention:

1. An applicator for applying a tubular bandage to a part of the body, comprising two pairs of wire skeleton fingers of substantially the same size and configuration, 10 each pair of fingers formed from a single piece of spring wire with the ends thereof abutted together, the two pair of opposed fingers arranged at right angles to each other, each pair of fingers comprising looped end portions and a common shank portion formed therebetween, 15 said shank portions bent forming each pair of fingers into a U-shaped member to cause said fingers to inherently tend to separate radially, the shank portions between said bends maintained in closely adjacent relationship crossing and joining each other intermediate the bends 20 therein to form a unitary structure and a single ring slideable on said shank portions adjacent the looped end portions to hold the fingers under tension.

2. An applicator for applying a tubular bandage to a part of the body, comprising a plurality of pairs of 25 wire skeleton fingers, each pair of fingers formed from a single piece of spring wire with the ends thereof abutted together, each pair of fingers comprising looped end portions and a common shank portion formed therebetween, said shank portions bent forming each pair of fingers 30 into a U-shaped member to cause said fingers to inherently tend to separate radially, and the shank portions between said bends crossing and joining each other intermediate the bends therein to form a unitary structure and circumscribing means slideable on the shank portions adjacent the looped end portions to selectively hold the fingers against separation.

3. An applicator for applying a tubular bandage to a part of a patient's body, comprising a plurality of pairs of elongated spaced resilient wire fingers over which a 40 tubular bandage may be drawn and inside of which fingers a part of the patient's body may be received while applying the bandage, said pairs of fingers adapted to carry a length of tubular bandage thereon whereby the applicator may be twisted and by retroverting the same 45 over a part of a patient's body to dispense the bandage in successive layers on such part, said pairs of fingers embodying looped end portions and a double strand shank portion intermediate said loops, said shank portion of each pair of fingers being rigidly joined together at 50 their mid-section, each pair of fingers formed into substantially U shape configuration by arcuate bends applied to the shank portions thereof, said arcuate bends causing the fingers to tend to separate further in the free portions thereof, and a loop embracing and sliding upon all 55 of said shank portions adjacent said looped end portions to selectively hold the fingers substantially parallel.

4. An applicator for applying a tubular bandage to a part of the body, comprising two pairs of elongated wire skeleton fingers of substantially the same size and configuration with their shank portions rigidly secured together, said fingers being circumferentially spaced and arranged at right angles to each other and in general defining a tubular socket over which a bandage may be drawn and into which a part of the body is received 60 when the bandage is applied, each pair of skeleton fingers formed solely of and from a single continuous piece of wire formed with the ends thereof abutted together and forming a double strand section of wire, each section of wire providing an open elongated loop of wire at the opposite ends thereof with a closed common shank portion intermediate each of said loops, said shank portion bent to form each pair of fingers into a U-shaped member with a pair of outwardly extending portions and a transverse connection section, the fingers of one pair 65 being arranged at right angles to the fingers of the other 70 75

pair, the shank portion of each pair of fingers crossing each other and joined together at the junction of the transverse connection sections, an arcuate bend in each of the shank portions at the junction of each of the transverse connection sections and the outwardly extending portions thereof to cause the fingers to tend to separate further in the free portions thereof and a one piece circular ring slidably mounted upon all of said finger shank portions to hold said fingers parallel with each other.

5. An applicator for applying a tubular bandage to a part of the body, comprising two pairs of elongated wire skeleton fingers rigidly secured together, said fingers being circumferentially spaced and in general defining a tubular socket over which a bandage may be drawn and into which a part of the body is received when the bandage is applied, each pair of skeleton fingers formed solely of and from a single continuous piece of wire formed with the ends thereof abutted together and forming a double strand section of wire, each section of wire providing an open elongated loop of wire at the opposite ends thereof with a closed common shank portion intermediate each of said loops, said shank portion bent to

form each pair of fingers into a U-shaped member with a pair of outwardly extending portions and a transverse connection section, the fingers of one pair being arranged at right angles to the fingers of the other pair, the shank portion of each pair of fingers crossing each other and joined together at the junction of the transverse connection sections, and an arcuate bend in each of the shank portions at the junction of each of the transverse connection sections and the outwardly extending portions thereof to cause the fingers to tend to separate further in the free portions thereof, and a movable circular loop embracing and slideable on the exterior surfaces of all of said outwardly extending shank portions of the fingers to selectively hold the loop portions of the fingers substantially parallel with each other.
